EAR MUFF BAND

Filed Dec. 9, 1947

FIG. 5.

FIG. 6.

INVENTOR.
IRVING GOLDMAN

BY *Isaac Sholechoff*
ATTORNEY

UNITED STATES PATENT OFFICE

2,504,826

EAR MUFF BAND

Irving Goldman, Brooklyn, N. Y.

Application December 9, 1947, Serial No. 790,477

3 Claims. (Cl. 2—209)

1

This invention relates to new and useful improvements in ear muffs, and, more particularly, aims to provide a novel and valuable device incorporating a pair of ear muffs, one for each ear, and a coupling and carrying instrumentality therefor complete in and of itself as such instrumentality, and not a part of or an appendage to a hat, cap or the like.

An object of the invention is to provide an ear muff assemblage as above wherein said instrumentality is freely and substantially limply flexible, and preferably elastically flexible in a certain part thereof, whereby the muffs may always be properly protectively placed over the ears of the wearer, there to be held without discomfort and without undue conspicuousness, and with these results obtained whether or not, with said instrumentality having end portions to be tied, said end portions are tied under the chin or at the back of the head of the wearer.

While in combination with these features muffs of a previously known type are employed, a feature of the invention is that there is a special coaction between structural elements of each such muff and the connections of portions of said instrumentality thereto, for allowing ready shift of the locations of these connections in directions paralleling the peripheral curvatures of the muffs, thereby to adapt the ear muff assemblage for quick rearrangement thereof, to match ear settings peculiar to a particular wearer and also for quick rearrangement of said assemblage for most dependable securement in the case either where the portions to be tied are tied under the chin or where said portions are tied at the back of the head of the wearer.

A further object of the invention, in connection with all the foregoing, is to provide a simple and efficient ear muff assemblage, and one wherein all portions of said instrumentality are very limply flexible, and all portions of said instrumentality, including said preferably present elastically flexible part thereof, are of very inexpensive materials, are capable of being formed without waste of said materials, and are interconnect- ed with other parts of the assemblage by easily applied means of exceptionally low cost.

Various other objects, features and advantages will be explained or become apparent hereinafter.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view, showing a now favored embodiment of the invention, in use, with the end portions of said instrumentality tied below the chin of a wearer.

Fig. 2 is also a perspective view, showing the ear muff assemblage removed from the wearer, and with one of the ear muffs removed from a part of said instrumentality, said part being a carrying frame for an ear muff, and part of the other ear muff broken away.

Fig. 3 is an enlarged fragmentary detail view, being a section taken on the line 3—3 of Fig. 2.

Fig. 4 is a perspective of an ear muff, detached. Fig. 5 is a perspective view, showing the ear muff assemblage in use, but with the end portions of said instrumentality tied at the back of the head of a wearer.

Fig. 6 is a perspective view showing the position assumed by the mouth of the pouch when the tapes are under longitudinal stress.

Referring to the drawings more in detail, each ear muff 10 comprises what may be called a pouch 25 of substantially circular outline, and made of any suitable pliable and warm material. As here indicated, the material used is desirably a villous or furry one, preferably such a triflingly inexpensive one as lambskin. A substantially circular piece of this material has stitched thereon, and to its side opposite to its furry side, an encircling elastic tape 11. The marginal portion of said piece may be slightly ruffled or gathered during the stitching. After attachment of the tape 11 is completed by said stitching, the pouch is turned 30 inside out, to provide the structure illustrated in Fig. 4.

Thus at its inner side said structure has an elastically distensible mouth 12, surrounded by 40 an internal annular chamber 14 distensible with the mouth 12; these distensions being sufficient to permit ready insertion and removal of an oval carrying frame 15, as one of metal, plastic or the like.

The carrying instrumentality comprises, in addition to the frame 15 and the like frame not shown because it is inside the muff 10 at the left in Fig. 2, a plurality of limply flexible elongate portions consisting of a pair of tie tapes 16 and 50 17, a pair of connector tapes 18 and 19, and an elastic interponent 20 between the tapes 18 and 19. Said tapes 16—19 are satisfactory when constituted by straight cut off lengths of any low cost tape, preferably one of double-selvaged 55 cotton ribbon character. Said interponent is de-

sirably in the form of an endless loop of ordinary round elastic tape.

The upper end of the tape 16 is turned back on itself over an end of the frame 15, and secured by applying two small metal eyelets through the two plies of the tape as indicated at 21. The upper end of the tape 17 is similarly connected to the other frame which corresponds to the frame 15.

The connector tape 18, for flexibly joining the ring 15 and the elastic interponent 20, is connected to the latter at the bight between an upper length 18^a and a lower length 18^b of the tape 18, and the length 18^b has an end portion folded back so that the frame 15 is engaged at the bight between the length 18^b and said portion 18^c; a pair of small metal eyelets being applied to lock the parts 18^a, 18^b and 18^c together as indicated at 22, and a pair of such eyelets being also applied to lock the parts 18^a and 18^b together as indicated at 23.

The connector tape 19, for flexibly joining the elastic interponent 20 and the other ring corresponding to the ring 15, is arranged and eyeleted together as just explained in connection with the tape 18.

In use, the elastic interponent 20 comfortably rests on the top of the head of the wearer, even with the tapes 18 and 19 of narrow width and in that case also even with these tapes accidentally twisted. The stretchability of said interponent, moreover, allows the muffs 10 to be placed exactly as they should be placed on the ears of the wearer regardless of largely different settings thereof on the head. Also, so as to take care of exceptionally large sized heads, the device may be supplied in a number of sizes, merely by use of elastic interponents of different lengths.

In Fig. 1, the device is shown as applied with the tapes 16 and 17 tied into a bow-knot under the chin. In Fig. 5, the device is shown as applied with these tapes tied at the back of the head. It will be noted from Fig. 5 that the direction of extension of the tape 16 is at an angle to the direction of extension of the tape 18, as contradistinguished from the arrangement of these parts in Fig. 2. This is a feature of the invention resulting from the use, in connection with muffs 10 constructed as above described and having the attributes pointed out, of the tape elements of the invention, and the loose connections between the ends thereof and the frame 15 in one of the muffs and the corresponding frame in the other muff, such loose connections being provided by slightly spacing the eyelets 21 and 22 from the ring 15 and similarly spacing from the other ring the corresponding eyelets applied to the tapes 17 and 19.

When the ear muff assembly is secured in position, the tapes 18 and 19, the frames 15 and the tie tapes 16 and 17 assume longitudinal aligned positions, as shown in Fig. 6, distorting the elastic tapes 11 which assume oval shapes between the tapes 16, 18 and 17, 19 and hold the pouches in position on the frames 15.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In an ear muff assembly having a pair of ear muffs for engagement over one's ears and each including a rigid frame enclosed within a pouch of cloth material and having extendable mouth openings and tie tapes having ends attached to the rigid frames and depended therefrom to have their free ends tied beneath one's chin, resilient means for extension across the top of one's head and connected with said rigid frames at its ends, said resilient means comprising a continuous elastic loop interposed between the ear muffs on the sides opposite the sides from which the tie tapes extend, connector tapes having their intermediate portions passing through diametrically opposite sides of said elastic loop, said connector tapes having their free ends superimposed after being passed through said elastic loop and extended in opposite directions therefrom and passed through the adjacent sides of the rigid frames of the ear muffs and doubled over upon themselves, and means securing together the doubled over ends of said connector tapes to prevent disengagement thereof from the rigid frames.

2. In an ear muff assembly having a pair of ear muffs for engagement over one's ears and each including a rigid frame enclosed within a pouch of cloth material and having extendable mouth openings and tie tapes having ends attached to the rigid frames and depended therefrom to have their free ends tied beneath one's chin, resilient means for extension across the top of one's head and connected with said rigid frames at its ends, said resilient means comprising a continuous elastic loop interposed between the ear muffs on the sides opposite the sides from which the tie tapes extend, connector tapes having their intermediate portions passing through diametrically opposite sides of said elastic loop, said connector tapes having their free ends superimposed after being passed through said elastic loop and extended in opposite directions therefrom and passed through the adjacent sides of the rigid frames of the ear muffs and doubled over upon themselves, and means securing together the doubled over ends of said connector tapes to prevent disengagement thereof from the rigid frames, said securing means comprises eyelets passed through the doubled over ends of said connector tapes.

3. In an ear muff assembly having a pair of ear muffs for engagement over one's ears and each including a rigid frame enclosed within a pouch of cloth material and having extendable mouth openings and tie tapes having ends attached to the rigid frames and depended therefrom to have their free ends tied beneath one's chin, resilient means for extension across the top of one's head and connected with said rigid frames at its ends, said resilient means comprising a continuous elastic loop interposed between the ear muffs on the sides opposite the sides from which the tie tapes extend, connector tapes having their intermediate portions passing through diametrically opposite sides of said elastic loop, said connector tapes having their free ends superimposed after being passed through said elastic loop and extended in opposite directions therefrom and passed through the adjacent sides of the rigid frames of the ear muffs and doubled over upon themselves, and means securing together the doubled over ends of said connector tapes to prevent disengagement thereof from the rigid frames, and eyelets passing through the superimposed layers of said connector tapes.

closely adjacent said elastic loop preventing longitudinal movement of said elastic loop between the adjacent faces of the superimposed layers of said connector tapes.
